UNITED STATES PATENT OFFICE.

HARRY F. CORNING, OF HARTFORD, CONNECTICUT.

DESIGN FOR MARTINGALE-RINGS.

Specification forming part of Design No. 7,961, dated December 29, 1874; application filed May 12, 1874.
 [Term of Patent 14 years.]

To all whom it may concern.

Be it known that I, HARRY F. CORNING, of Hartford, in the county of Hartford and State of Connecticut, have invented or produced a new and original Design for a Martingale-Ring, of which the following is a specification, reference being had to the accompanying drawing, where—

Figure 1 is a perspective view of the ring attached to a martingale-strap, and with a rein running through the ring. Fig. 2 is a side view of the ring. Fig. 3 is a view of the same in cross-section on the line *x x*.

These rings are commonly made of hard rubber, and a proper size is, for this design, one and a half inch high by five-eighths of an inch wide, inside measurement.

The body of the ring *a* (see Fig. 3) is round, with a raised and ornamental rib, *b*, all around

the outside. The shape of the body of this ring in cross-section is the same at all points, and that cross-section is, aside from the raised ornamental rib or wing, a circle. The two longer sides rise from the base in parallel lines and at right angles to the base, and the upper parts of the two longer sides unite in a part-circular arch.

The general shape is fully shown in the drawing.

I claim as my invention or production—

The design for a martingale-ring having the features hereinbefore described, and an appearance as shown in the drawings.

HARRY F. CORNING.
